UNITED STATES PATENT OFFICE.

SIDNEY H. SHORT, OF CLEVELAND, OHIO, ASSIGNOR TO THE SHORT ELECTRIC RAILWAY COMPANY, OF SAME PLACE.

TURN-OUT AND CROSSING FOR LINE CONDUCTORS.

SPECIFICATION forming part of Letters Patent No. 447,495, dated March 3, 1891.

Application filed April 12, 1890. Serial No. 347,632. (No model.)

To all whom it may concern:

Be it known that I, SIDNEY H. SHORT, of Cleveland, in the county of Cuyahoga and State of Ohio, have invented certain new and 5 useful Improvements in Turn-Outs and Crossings in Overhead and Underground Line Conductors for Electric Railways; and I do hereby declare the following to be a full, clear, and exact description of the invention, such as will 10 enable others skilled in the art to which it app pertains to make and use the same.

This invention has reference to turn-outs and crossings in overhead and underground line conductors for electric railways; and the 15 invention is particularly designed for electric railways employing two overhead or underground line or trolley conductors in a round metallic circuit for conveying the current by means of traveling contacts to and from the 20 motor on the car.

The object of my improvement is to provide such turn-outs for the line conductors as will permit an uninterrupted working of the system without requiring the special attention of the motor-man or engineer and without interference of the conductors and trolleys of a trunk-line with the conductors of a branch line or siding. This will more fully 25 appear from the following detailed description, in which reference is made to the accompanying drawing, in which is shown a perspective view of a portion of a two-wire overhead system, showing my invention applied to a turn-out in a main or trunk line.

Referring to the drawings, there are shown 30 two overhead line-wires 1 2, constituting the positive and negative conductors of a round metallic circuit for a main or trunk line, and there are also shown two other and similar 35 conductors 3 4, constituting a branch line and connected to the main line by curved sections 3' 4', which latter may be of sufficiently heavy material to retain their curved shape without the use of stays or other means for the 40 purpose, or which may be composed of continuations of the said conductors 3 4, formed as a polygon with very obtuse angles, as indicated in dotted lines, so as to be, in effect, a curve supported by stay or span wires— 45 such, for example, as indicated by dotted line 3—arranged in any suitable manner. The

curved sections 3' 4' are joined to the main or trunk line wires 1 2 by frogs or switches 5 of the character usually employed for this purpose, for which reason these frogs are neither 55 shown nor described in detail.

As shown, both the main and the branch line wires are supported from span-wires 6 by insulating-hangers 7 of any known and suitable construction, but the construction of 60 these hangers is neither shown nor described in detail, since such construction is immaterial for the purposes of the present invention. Each span-wire is preferably provided with an insulating-connector 8 between the conductors, so as to insure a complete insulation under all circumstances between the positive and negative conductors. The construction of the connectors 8 is fully shown and described in another application, No. 346,168, 65 filed by me April 1, 1890, and it is not deemed necessary to further describe it herein, since it forms no part of the present invention.

The curved section 3', branching from the positive conductor 1, crosses the negative conductor 2 before it is connected with or merges into the branch conductor 3, and is insulated therefrom in a manner and for a purpose which I will now describe.

Depending from the conductor 2 and extending to equal distances on each side of the curved section 3' is a double inclined guide or track 9, formed either wholly or in part of insulating material and merging at the ends into the under side of the said conductor 2. At the middle, where the guide or track 9 is widest, it is notched or cut away to form a recess 10, open at its lower end, and secured to the upper end of this recess there is an insulating-hanger 11, carrying the 75 curved section 3', and of such length that the said section 3' is above the lower open end of the notch or recess 10.

It will be understood that the notch or recess is of such width that a trolley-wheel 95 traveling on the curved section 3' will easily pass through it; but a trolley traveling on the conductor 2 will, when it reaches the guide 9, break contact with the said conductor, and then ride down one incline there- 100 of and up the other incline and ultimately again make contact with the conductor 2.

- The notch or recess 10, it will be observed, while wide enough to permit a trolley-wheel to pass on the section 3', is too narrow to permit a trolley-wheel traveling on the guide 5 9 to enter it. Therefore the trolley-wheel will readily pass from one incline to the other without experiencing a sensible break in its supporting-track from the break in the guide 9, caused by the said recess 10.
- 10 In a two-wire overhead system of conductors—such as illustrated in the drawings—the surface-car is provided with two independent trolleys connected, respectively, to the terminals of the electric motor on the car and making contact with the two overhead conductors—one with the positive and the other with the negative conductor—and in such case, as soon as the trolley traveling along the conductor 2 comes to the insulating guide or 15 track 9 the circuit through the motor-car is broken and is not again established until after the trolley has reached the other end of the said guide or track, thus effectually preventing a short circuit between the conductors 20 1 and 2, should the said trolley accidentally make contact with the curved section 3', since both wires 1 and 3' are positive wires.
- As will be readily understood, the break in the circuit through the electric motor on 30 the car, caused by the interposition of the insulating-guide 9 in the path of one of the two trolleys, is of short duration, and the momentum of the car will carry the trolley beyond such guide, so that the break in the circuit produces practically no effect.
- It will be noticed that when the car is switched onto the branch track, in which case it is usually driven at a slow rate and would quickly stop were the circuit broken, the 40 trolleys will remain at all times in contact with both curved sections 3' 4', and consequently the flow of current through the electric motor will remain constant and uninterrupted.
- If the curved branch-line conductor 3' were placed above the main-line conductor 2, where it crosses the same, the double inclined insulated or insulating track would of necessity be placed on the curved conductor, and there 50 would be a break in the motor-circuit at a point of travel where the speed is necessarily low. This would in many cases cause a stoppage of the motor-car, which is entirely avoided by my invention, as above set forth.
- The application of the invention to single-wire and underground systems will be at once apparent, and for this reason it is not deemed necessary to either illustrate or describe the same.
- Having thus fully described the invention, what I claim, and desire to secure by Letters Patent, is—

1. In a two-wire system of line conductors for electric railroads, the combination of the two trunk or main line trolley-wires with two 65 curved branch trolley-wires, one of which crosses a main wire and both affording continuous electric trolley contact, substantially as described.

2. The combination, with two main trolley-wires of opposite polarity, of two frogs or switches in said wires, two curved branched trolley-wires affording continuous electric trolley contact and connected with said frogs or switches, and an insulated section in one 75 main wire at the crossing between one of said branched trolley-wires and the said main wire of opposite polarity, substantially as described.

3. In a two-wire system of line conductors for electric railroads, the combination, with a 80 main or trunk line, of a curved turn-out from the main line having one of its conductors crossing but clearing the said main line below the latter and affording continuous electric trolley contact, and an insulating guide 85 or track on the crossed main-line conductor bridging the crossing turn-out conductor, substantially as described.

4. In a two-wire system of line conductors for electric railroads, the combination, with 90 the two conductors of a trunk or main line, one of which is provided with a double inclined and notched insulated or insulating track, of a turn-out or branch composed of a frog in each main conductor, a curved conductor extending from the frog on one main conductor underneath the other main conductor through the notch in the track, and another curved conductor extending from the other frog, substantially as described.

5. The combination, with two main trolley-wires and two frogs or switches in said wires, of two curved branched trolley-wires, one of which crosses a main wire below the latter and both connected with said frogs or switches, 105 a notched insulated or insulating track in the crossed main wire at the crossing, and a support for the crossing wire in the notch, substantially as described.

6. The combination, with a span-wire, of a 110 trolley-wire provided with a double inclined and notched track, an insulated support between said span-wire and said track above the notch therein, a crossing trolley-wire extending through the notch, and an insulator supporting the crossing wire in said notch, substantially as described.

In testimony whereof I have signed this specification in the presence of two subscribing witnesses.

SIDNEY H. SHORT.
